UNITED STATES PATENT OFFICE.

JOHN L. FAY AND SYLVESTER B. WAY, OF MILWAUKEE, WISCONSIN.

POLE-ELEVATION INDICATOR.

1,168,295.

Specification of Letters Patent.

Patented Jan. 18, 1916.

Application filed September 30, 1912. Serial No. 723,010.

To all whom it may concern:

Be it known that we, JOHN L. FAY and SYLVESTER B. WAY, citizens of the United States, and residents of Milwaukee, in the 5 county of Milwaukee and State of Wisconsin, have invented new and useful Improvements in Pole-Elevation Indicators, of which the following is a description, reference being had to the accompanying drawings, which are a part of this specification.

This invention relates to improvements in elevation indicators.

In telegraph, telephone and electric light systems it is considered good engineering 15 practice in crossing the wires of one system over the wires of another system to have the crossing wires at least five feet above the wires crossed and to accomplish this result, it is, of course, necessary to support the 20 wires on poles which are of sufficient length to give the desired elevation.

In ordinary practice it is customary for the foreman of the linemen of the system being built, to estimate the height of the 25 wires to be crossed and add five feet to this estimated length and also add the length of the pole to be inserted into the ground in order to get the total length of the pole desired for the particular crossing. In actual 30 practice the estimated height of the wires to be crossed is not always correct with the result that when the pole is in place it is found to be too long or too short. If too long, the expense of the system is increased 35 due to the increased cost of the unnecessary lengths of the poles leading up from the ordinary height of the poles to the elevated crossing. On the other hand if the estimated distance is too short, the poles would 40 have to be changed for longer ones or the company constructing the new line would be subject to suit for possible damage.

In order to approximately estimate the elevation it requires a lineman of long experience and at a comparatively high wage rate to keep the expense of construction 45 within a reasonable amount.

It is one of the objects of this invention to provide an elevation indicator which is 50 adapted to overcome the before mentioned objectionable features and correctly indicate the length of poles required to support cross wires the desired distance above the wires being crossed.

55 A further object of the invention is to provide an elevation indicator which will in-

dicate to the user thereof even though unskilled in construction work, the exact length of the pole required to support wires a predetermined distance above the wires 60 being crossed and also compensating for the predetermined distance the poles are set in the ground.

A further object of the invention is to provide an elevation indicator which is 65 simple in construction, inexpensive to manufacture and which is of a size to be conveniently carried in the pocket.

With the above and other objects in view, the invention consists of the improved elevation indicator and its parts and combinations as set forth in the claims, and all equivalents thereof.

In the accompanying drawing in which the same reference characters indicate the 75 same parts in all of the views: Figure 1 is a front side view of the improved elevation indicator; Fig. 2 is a rear side view thereof, parts broken away to show interior construction; Fig. 3 is a top view of a portion of the 80 elevation indicator, a portion broken away to show parts therebeneath; Fig. 4 is an end view of the outer portion of the elevation indicator; and Fig. 5 is a top view of the 85 mirror casing removed from the sighting tube of the elevation indicator.

Referring to the drawing, the numeral 8 indicates the sighting tube which is square in cross section and at one end is provided with a sight aperture 9 through which the 90 object to be measured is viewed. The opposite end of the sighting tube is provided with a removable mirror casing 10 having a mirror 11 positioned at an angle on one end, and covering one half of the open tubular 95 end of the casing. The opposite open end 12 of the mirror casing is divided centrally horizontally by a sight line 13. The mirror 11 is mounted at an angle of forty-five degrees to provide for reflecting the bubble of 100 the level 14, positioned above the sight tube, to permit the view thereof through the sight aperture, and the upper wall of the sight tube 8 at a point above the mirror is provided with an aperture 15 to permit the 105 bubble to be reflected therethrough.

A vertical arc 16 mounted on the side of the sight tube and projecting upwardly therefrom has pivotally connected thereto a rock frame 17 to which the level 14 is connected. The rock frame is mounted a sufficient distance above the sight tube to per-

mit the inclination of the sight tube to the desired extent within the range of the instrument and the level casing 18 is also provided with an opening 19 on its lower side 5 and in vertical alinement with the aperture 15 of the sight tube 8 to permit the bubble to be reflected on the mirror.

The rock frame is provided with a milled hand wheel 20, for convenience in holding or 10 turning the level in horizontal position while the sight tube is being adjusted or turned to the desired inclination, and is also provided with a screw 21 for locking the parts in adjusted position.

15 An indicator arm 22 depending downwardly from the rock frame, is adapted to co-act with a graduated scale 23 delineated on the outer face of the arc member 16 to indicate the length of a pole necessary to 20 support wires extending over and five feet above an obstruction. The graduations are spaced and marked to indicate the height of 25 the obstruction viewed plus five feet to be added to the pole and also plus the length 30 the pole is to be set into the ground to support wires extending over and five feet above said obstruction. In this particular embodiment of the invention as shown in 35 the drawing the graduations are marked and spaced to indicate poles varying five feet in 40 length from twenty-five to seventy-five feet long but is to be understood that the graduation may be changed to indicate other lengths, and also that the indicated length 45 of the part of the pole set into the ground may be varied with relation to the proportion it bears to the total length of the pole to come within good engineering practice without departing from the spirit and scope 50 of the invention. The present engineering practice provides for setting a twenty-five foot pole four and a half feet and a seventy-five foot pole seven and a half feet in the ground, and the poles of intermediate 55 lengths are set various proportional distances between these amounts.

In the particular indicator shown the 50 readings are to be taken at a point fifty feet from the base line of the obstruction to be passed over, but it is obvious that the graduations may be arranged for other distances.

Assuming that a line is to be extended over another line of wires or other obstruction twenty feet high, the user of the indicator would take a position fifty feet from

the base-line of the obstruction and sight through the instrument so that the cross line of the instrument would be in alinement with the top portion of the obstruction. The hand wheel of the level is now turned 60 to swing the level to a horizontal position and when the object viewed is in the same horizontal line with the reflected bubble of the level the observation is completed and it is only necessary to look at the number on 65 the scale pointed out by the indicator arm, which, in this example, would be 30, to know that a pole thirty feet long would be the proper length to be set five feet in the ground and would extend to a position to 70 support a cross wire five feet above the obstruction in question.

From the foregoing description it will be seen that the user does not have to make any calculation or estimate in getting the correct 75 length of a pole to support wires a given distance above wires crossed.

The instrument is of very simple construction and may be successfully used by persons not skilled in the particular work to which 80 it relates.

What we claim as our invention is:

1. A device of the character described for determining the varying unknown length of different poles, comprising an altimeter embodying an indicator arm and coöperating indicating characters, said characters representing numerically various total lengths which are in excess of and in varying proportion to the actual heights of the different 90 objects sighted.

2. A device of the character described for determining the varying unknown length of different poles, comprising an altimeter embodying an indicator arm and coöperating indicating characters, said characters representing numerically various total lengths which are in excess of and in varying proportion to the actual heights of the different objects sighted, means for manually operating said indicating arm, and a separate means for locking said indicating arm in its adjusted positions.

In testimony whereof, we affix our signatures, in presence of two witnesses:

JOHN L. FAY.
SYLVESTER B. WAY.
